(57) **CLAIM**

The ornamental design for a sling mount, as shown and described.

DESCRIPTION

FIG. 1 is a perspective view of a first embodiment of a sling mount, showing our new design;

FIG. 2 is another perspective view of the sling mount shown in FIG. 1;

FIG. 3 is a top plan view of the sling mount shown in FIG. 1;

FIG. 4 is a left side elevational view of the sling mount shown in FIG. 1;

FIG. 5 is a right side elevational view of the sling mount shown in FIG. 1;

FIG. 6 is a bottom plan view of the sling mount shown in FIG. 1;

FIG. 7 is a rear elevational view of the sling mount shown in FIG. 1;

FIG. 8 is a front elevational view of the sling mount shown in FIG. 1;

FIG. 9 is a perspective view of a second embodiment of the sling mount, showing our new design;

FIG. 10 is another perspective view of the sling mount shown in FIG. 9;

FIG. 11 is a top plan view of the sling mount shown in FIG. 9;

FIG. 12 is a left side elevational view of the sling mount shown in FIG. 9;

FIG. 13 is a right side elevational view of the sling mount shown in FIG. 9;

FIG. 14 is a bottom plan view of the sling mount shown in FIG. 9;

FIG. 15 is a rear elevational view of the sling mount shown in FIG. 9; and,

FIG. 16 is a front elevational view of the sling mount shown in FIG. 9.

The broken lines shown in the Figures are included for the purpose of illustrating portions of the sling mount that form no part of the claimed design.

1 Claim, 16 Drawing Sheets
